US0D1084494S

(12) **United States Design Patent** (10) **Patent No.:** **US D1,084,494 S**
(45) **Date of Patent:** **** Jul. 15, 2025**

(54) **AEROSOL GENERATOR**

- (71) Applicant: **Nicoventures Trading Limited**,
London (GB)
- (72) Inventors: **Jusuek Lee**, London (GB); **Jiyoun Kim**, London (GB); **Kang Min Kim**, London (GB); **Jonathon Lister**, London (GB)
- (73) Assignee: **Nicoventures Trading Limited**,
London (GB)
- (**) Term: **15 Years**
- (21) Appl. No.: **29/884,871**
- (22) Filed: **Feb. 16, 2023**

(30) **Foreign Application Priority Data**

(57) **CLAIM**

The ornamental design for an aerosol generator as shown and described.

DESCRIPTION

FIG. 1 is a top front perspective view of an aerosol generator showing the claimed design;

FIG. 2 is a bottom rear perspective view thereof;

FIG. 3 is a bottom front perspective view thereof;

FIG. 4 is a front view thereof;

FIG. 5 is a rear view thereof;

FIG. 6 is a top view thereof;

FIG. 7 is a bottom view thereof;

FIG. 8 is a left view thereof;

FIG. 9 is a right view thereof; and,

FIG. 10 is a partial detail view of FIG. 1.

The dot-dash broken lines in FIG. 10 illustrate the boundaries of the partial detail view of the aerosol generator that form no part of the claimed design.

1 Claim, 10 Drawing Sheets
